his attorney.

UNITED STATES PATENT OFFICE.

MARK E. FERNALD, OF SAUGUS, MASSACHUSETTS, ASSIGNOR TO C. C. BLAKE, INCORPORATED, OF BOSTON, MASSACHUSETTS, A CORPORATION OF NEW YORK.

LAST.

1,283,128.

specification of Letters Patent.

Patented Oct. 29, 1912

Application filed November 4, 1915. Serial No. 59,644.

To all whom it may concern:

Be it known that I, MARK E. FERNALD, a citizen of the United States, residing at Saugus, in the county of Essex and State of Massachusetts, have invented a new and useful Improvement in Lasts, of which the following is a specification.

The present invention relates to lasts, and more particularly to lasts for use in the manufacture of welt shoes.

As well known to those skilled in the art lasts for welt shoes are developed from a pattern identical in shape with the insole to be used with the last in the manufacture of the shoe. If this pattern is mislaid or destroyed it is impossible to determine from the last the exact shape of the proper insole for use therewith owing to the manner in which the lines of the bottom and body portion of the last merge at the shank portions thereof.

One object of the present invention is to produce a last, for a welt shoe, having means thereon for indicating the shape of the insole for use therewith.

To the accomplishment of this object a feature of the present invention contemplates the provision in a wooden last, for a welt shoe, of a permanent record cut into the last bottom of the shape of the insole to be used therewith in the manufacture of the shoe.

Broadly considered this record may take any form found desirable or expedient. It is preferred, however, to separate the bottom of the last from the body portion thereof by an abrupt shoulder so that the proper insole for use with the last may be readily determined by inspection.

Another object of the present invention is to produce a last through the use of which an important economy in sole stock material may be effected without reducing the quality of the shoes made on the last.

Accordingly another feature of the invention contemplates the provision of a last having a bottom penetrable throughout the area of its forepart by tacks and having the area of its bottom at the forepart considerably less than the area bounded by the projections of the upper-shaping surface of the last at the forepart upon the plane of the last bottom.

In its broader aspects the invention contemplates the reduction of the area of the

last bottom at the forepart thereof by making the last bottom shorter in length or narrower in width or both shorter in length and narrower in width than the area bounded by the projections of the upper-shaping surface of the last at the forepart upon the plane of the last bottom.

For a long time it has been the practice to secure insoles to lasts by a few tacks driven through the median line of the insole. With this method an anvil may be readily inserted between the insole and the last during an insole trimming operation to prevent the knife cutting into the last. It is now proposed to cement insoles to their lasts. Although the proposed method is superior to the former method an anvil may not be used as the insole is securely attached to the marginal portion of the last thus preventing the penetration of the anvil between the last and insole.

Another object of the present invention is to produce a last constructed to permit an insole trimming operation on the last without injury thereto.

With this object in view a further feature of the present invention contemplates the provision in a last having either a bottom integral with the last or a bottom penetrable throughout the area of its forepart by tacks, of a vertical shoulder separating the bottom of the last from the upper shaping surface thereof. With this construction the knife may pass through the insole without contacting with the upper shaping surface thereof. This feature of the invention may be used to advantage even if the insole is secured to the last by the usual insole tacks.

Other features of the invention consist in certain combinations and arrangements of parts fully set forth hereinafter, the advantages of which will be readily understood by those skilled in the art.

The various features of the present invention will be readily understood from an inspection of the accompanying drawings illustrating the best form of the invention at present known to the inventor, in which,

Figure 1 is a plan of the last;

Fig. 2 is an elevation; and

Fig. 3 is a sectional elevation.

In the illustrated embodiment of the invention the wooden last is provided with an upper-shaping surface 1 and a bottom 2 integral therewith which receives the insole to be used with the last in the manufacture of

a welt shoe. The upper-shaping surface 1 and bottom 2 are separated by a vertical shoulder 3 extending from a point adjacent the breast line on one side of the last to the 5 breast line on the other side of the last. If the last is to be used in the manufacture of a shoe which is sewn around the heelseat thereof the vertical shoulder 3 will, of course, extend around the heel of the last.

10 By forming the shoulder 3 the last bottom is raised above the body portion of the last thus sharply defining the shape of the edge 4 of the last bottom. With a last constructed in the manner described the shape 15 of the insole for use therewith is readily found by inspection or by placing sheet material on the last and rubbing the sheet material to imprint the edge 4 thereon.

As shown in Fig. 1 the area of the last 20 bottom 2 at the forepart thereof is considerably less than the area bounded by the projections of the upper-shaping surface 1 upon the plane of the last bottom. This construction produces the overhang which is a desirable feature of Blake welt shoes. Furthermore, the reduction in the area of the 25 last bottom at the forepart permits a reduction in the size of the insoles and outsoles for use with the last thus effecting a considerable saving in the cost of production 30 without sacrificing the quality or appearance of the finished shoe.

It will be clear to those skilled in this class of devices and with the general objects of the present invention in view that changes may be made in the details of structure, the described and illustrated embodiment thereof being intended as an exploitation of its underlying essentials the features 35 whereof are definitely stated in their true scope in the claims hereto appended.

What is claimed as new, is:—

1. A wooden last for a welt shoe having a permanent record cut into its bottom in the 40 shape of the forepart and shank of the insole to be used therewith in the manufacture of the shoe.

2. A last for a welt shoe comprising an upper-shaping surface and a bottom integral therewith, the bottom along the shank

and forepart of the last being separated from the upper-shaping surface by an abrupt shoulder.

3. A last for a welt shoe having a bottom penetrable throughout the area of its forepart by tacks and having a vertical shoulder separating the bottom of the last from the upper-shaping surface thereof. 55

4. A last for a welt shoe having a bottom penetrable throughout the area of its forepart by tacks and having the area of its bottom at the forepart less than the area bounded by the projections of the body portion of the last at the forepart upon the plane of the last bottom. 60

5. A last for a welt shoe comprising an upper-shaping surface and a bottom penetrable throughout the area of its forepart by tacks, said upper-shaping surface and bottom being relatively arranged to provide an overhang at the forepart of the last. 70

6. A last for a welt shoe having the bottom thereon integral with the body portion of the last and shorter in length than the last. 75

7. A last for a welt shoe having the bottom thereon integral with the body portion of the last, said bottom at the forepart being narrower in width than the upper-shaping surface of the last at the forepart thereof. 80

8. A last for a welt shoe having the bottom thereon integral with the body portion of the last and shorter in length and narrower in width than the last. 85

9. A last for a welt shoe having a bottom thereon penetrable throughout the area of its forepart by tacks and having a vertical shoulder at the edge of the bottom extending from a point near the breast line on one side of the last to the breast line on the other. 90

10. A last for a welt shoe having an integral bottom, the edge of which from a point adjacent the breast line on one side of the last to a point adjacent the breast line on the other side of the last is located within the projections of the upper-shaping surface of the last upon the plane of the last bottom. 95

MARK E. FERNALD.
